APPARATUS FOR AND METHOD OF GENERATING AND SUPERHEATING STEAM

Julian R. Murray, Skokie, and Jackson E. O'Connell, Elmhurst, Ill., assignors to The Babcock & Wilcox Company, New York, N.Y., a corporation of New Jersey

Filed July 13, 1956, Ser. No. 597,655
8 Claims. (Cl. 122—33)

This invention relates to the art of steam generation and steam superheating. More particularly, the invention relates to the generation of high pressure (i.e. 2400 p.s.i.) steam in a fuel fired unit including a gas heated steam superheater, the initial superheating of relatively low pressure steam (350 p.s.i.) by indirect heat transfer involving the condensing of all of the high pressure steam, the return of the condensate to the high pressure steam generation, the subsequent superheating of the low pressure steam in a plurality of stages in the gas heated superheater of the unit, and provisions whereby the gas heated superheater of the unit may, alternatively, superheat the high pressure steam when low pressure steam is not available, the latter provisions functionally eliminating the initial superheating by indirect heat exchange and effecting steam flow directly from the zone of generation of high pressure steam to the gas heated superheater of the unit.

The steam generating and steam superheating unit of the invention is particularly applicable to a power plant having a plural pressure stage steam turbine means with a lower pressure stage of the turbine means receiving 1100° F. steam at a relatively low pressure (i.e. 350 p.s.i.a or 600 p.s.i.a) and generated by a nuclear reactor, and with the high pressure stage of the turbine receiving relatively higher pressure steam.

The invention is exemplified in a steam generating and superheating unit in which relatively low pressure steam derived from a source independent of the unit is superheated in a plurality of stages in a separately fired superheater. The latter preferably includes a high pressure steam generating section in which the steam is generated predominantly in the wall tubes of a fuel fired furnace. Saturated steam from this high pressure source is adapted to transmit heat by indirect heat exchange to the low pressure steam to superheat the latter in a first stage of superheating, with high pressure steam being condensed in this superheating stage. The low pressure steam heated in this initial superheating stage then passes through successive other superheating stages formed by the gas heated superheating means of the separately fired superheater, or high pressure steam unit.

The invention may be regarded as including a separately fired superheater burning a fossil fuel or a slag forming fuel at combustion temperatures in excess of 2200° F. and having a high capacity for superheating relatively low pressure steam. The separately fired superheater of the invention is characterized by high availability and low furnace chamber wall maintenance by its inclusion in the furnace chamber walls adjacent the active combustion zone of steam generating tubes operating at the saturation temperature of the high pressure steam, while the wall portions of the furnace chamber beyond the active combustion zone in a gas flow sense contain radiant superheater wall tubes forming one stage or part of the superheating means and normally receiving the low pressure steam from the independent steam generating source.

The invention particularly involves means whereby the power plant may be operated solely by steam generated in the unit when the nuclear reactor or other independent source of relatively low pressure steam is shut down.

2

Under these circumstances, the steam generated in the unit flows directly through the gas heated superheater means of the unit, the normal communication between the gas heated superheater means and the independent source of relatively low pressure steam being shut off, and the normal communication for high pressure steam flow to the initial superheating stage and the normal communication for the flow of condensate from the initial superheating stage of the relatively low pressure steam being likewise shut off. Under these circumstances the non-radioactive steam generated in the normally high pressure steam generating section may act as a washing agent to wash out or dilute radioactive deposits in the superheating means and other parts of the power plant such as the condenser and feed-water heaters. The invention, as indicated immediately above, may be considered as providing for the continuous service of the unit involving the high pressure steam generator and the gas heated superheating means normally for superheating relatively low pressure steam, rather than necessarily shutting down the whole power plant when the reactor is shut down. This decreases the chance of oxygen pickup in the system, and resulting corrosion. The invention may thus involve a substantial decrease in the original cost of the power plant by permitting the use of carbon steel in the feedwater heaters and associated equipment, in place of stainless steel, the cost of which is many times that of the carbon steel.

The invention will be clearly and concisely set forth in the claims appended hereto, but for a more complete understanding of the invention, its advantages and uses, reference should be had to the following description which refers to the attached drawing, showing a preferred embodiment of apparatus involved in the invention.

35 The drawing is a somewhat diagrammatic side sectional view indicating the high pressure condensing steam generating unit involving gas heated steam superheating means which normally functions solely to superheat relatively low pressure from an independent source.

30 40 In normal operation of the unit shown in the drawing, low pressure (i.e., 350 p.s.i.a. or 600 p.s.i.a.) steam from an independent source 10, such as a nuclear reactor, passes through the line 12 to the inlet 14 of the first superheating stage. Here the relatively low pressure steam is 45 superheated by indirect heat transfer in the heat exchanger 16. This heat exchanger receives, through the conduit 18, high pressure steam (i.e. 2400 p.s.i.a.) from the steam and water drum 20 of the high pressure steam generating system or section, of the fuel fired superheater.

50 55 60 This high pressure steam passes to the inlet chamber 22 of the heat exchanger 16, and then through a plurality of spaced tubes 24 having their inlet ends fixed within the tube sheet 26 and their outlet ends fixed within the tube sheet 28. The outlet ends of these tubes communicate with the intermediate high pressure steam chamber 29 from which the high pressure steam (or its condensate) passes through a series of spaced tubes 30 to the condensate outlet chamber 32. The condensate of the high pressure steam flows from the chamber 32 through one or more conduits 34 to the water space of the drum 20.

65 70 75 The tubes 24 and 30 are disposed within a hollow cylinder shell 36 which receives the low pressure steam through the inlet 14. This low pressure steam is initially superheated in the heat exchanger 16 from which it is conducted through one or more conduits 38 to a second superheating stage. The shell 36 of the heat exchanger 16 is in pressure-tight relationship with the tube sheets 26 and 28 at the opposite ends of the heat exchanger.

The steam initially superheated in the heat exchanger 16 passes through the conduits 38 to the horizontal header 40. From this header the steam flows through a row of

tubes, the first sections 42 of which extend along the roof of the horizontal gas pass 44 of the unit. The flow then continues through the upright and widely spaced screen sections 46 and 48 between which the heating gases exit from the gas pass and then flow past the dampers 50 into the flue 52 leading to the air heater 54. From the upright screen sections 46 and 48, the steam flow continues through the gas pass floor tube sections 56 to the header 58. From this header, the steam flows through a series of connecting tubes such as 60 to sidewall headers, one of which is indicated at 62. Leading upwardly from each of the side wall headers such as 62, there is a row of superheater wall tubes 64. The upper and outlet ends of these tubes are connected to discharge into one of the upper sidewall headers 65. From these sidewall headers, the steam passes through connecting tubes 66 and 68 to the header 70 from which the steam flows downwardly through the inlet tubular sections 72 of closely spaced and serially connected return bend tubes constituting the banks 74 and 78 of convection superheater tubes, the outlet sections 80 of which are in communication with the header 82.

From the header 82, the steam flow continues downwardly through one or more conduits 84 to the header means or header section 86. This header means may include four connected header sections one of which is located along each of the 4 sides of the furnace chamber 88. These header sections are preferably connected so that they all receive steam through the conduits 84, one of the header sections being indicated at 90 at the front wall 92 of the furnace chamber and opposite the header section 86 disposed adjacent the rear furnace chamber wall 94. From the header sections such as 86 and 90, the steam flows upwardly through radiant superheater wall tubes along the walls of the furnace chamber 88, some of these tubes being indicated at 96 and 98. The flow of steam continues through these tubes to the header 100 from which the steam flows as indicated by the arrows 102 and 104 through the connecting tubes 106 to the header 108.

Steam flowing through the side-wall header sections similar to the front and rear wall header sections 90 and 86 enters the upper side wall headers such as 110 and then flows, as indicated by the arrow 112 to the header 108 through the connecting tubes 114. From the header 108, the steam flows through a multiplicity of spaced and serially connected return bend tubes constituting the banks of secondary superheater tubes 116-118. The outlet ends of these tubes are connected to the header 120 from which the highly heated superheated steam flows through one or more conduits 122, to a stage of a steam turbine.

The unit shown in the drawings includes a coal-fired cyclone furnace 130 preferably of the type shown in the U.S. Patent to Kerr et al. 2,594,312 of April 29, 1952. High temperature furnace gases pass from this furnace through its throat 134 into the primary furnace chamber 136 and thence across the steam generating screen tubes 138 into the secondary furnace chamber 88, the walls of the cyclone furnace, the primary furnace chamber 136 and the lower rear wall of the secondary furnace including steam generating tubes. Above the level 140, the walls of the secondary furnace chamber are lined with radiant steam superheater tubes as previously indicated, and below the level 140 the walls of the primary furnace chamber 136 and the lower part of the secondary furnace chamber 88 include steam generating tubes having their inlet ends in communication with the lower header or drum 142 and their upper ends connected to header means such as the header sections 144 and 146 which, in turn, are appropriately connected by risers such as 148 with the steam and water inlet space of the drum 20. In this drum, the incoming mixtures of steam and water are subject to the fluid separating action of steam and water separators preferably of the type shown in the U.S. Patent to Rowand et al. 2,289,970 of July 14, 1942, and

the separated water passes through one or more large diameter downcomers such as 150 to the lower drum or header 142.

The lower headers for the cyclone furnace, such as 5 the header 152, are directly connected by circulators 154, with the header or drum 142 and it is to be understood that the tubes forming parts of the walls of the cyclone furnace have their outlet ends connected to one or more headers such as 156, the latter being directly connected 10 by the risers 158 to the steam and water mixture receiving space of the drum 20.

The refractory covered floor 160 of the primary furnace chamber 136 includes the floor tube sections 162 of some of the steam generating tubes leading directly from the drum or header 142 along the floor and then along the wall component 164 of the primary furnace chamber. Thence these tubes lead through the walls of the throat 134 and then through the wall component 166 of the primary furnace chamber. Other tubes directly connecting 20 the drum or header 142 and the header means 144 involve the screen sections 138 and also successive tubular sections in the wall 168 separating the primary furnace chamber 136 from the lower part of the secondary furnace chamber 88.

25 The side wall headers 170 for the primary furnace chamber and the lower part of the secondary furnace chamber are appropriately connected by circulators 172 with the header or drum 142, and the wall tubes extending upwardly from the headers 170 to side wall headers such as the header sections 144 and 146 adjacent the level 140 are preferably covered on their furnace sides with high temperature refractory thermally and mechanically maintained therein by metallic studs secured to the tubes in good heat transfer relationship and extending into the refractory metal in the manner indicated in the patent to Bailey 2,239,662 of April 22, 1941.

Others of the tubes leading upwardly from the lower drum or header 142 include the wall tube sections 174 disposed along the rear wall 176 of the lower portion of the secondary furnace chamber 88 and joined at their upper ends to the header section 146.

30 The superheater headers above the furnace chamber 88 and above the horizontal gas pass 44, and the tubular connections between those headers are enclosed within a casing which is preferably gas tight and which is constructed so as to afford thermal insulation. This casing is indicated in the drawing as having a roof section 200, a rear wall section 202, drum enclosing sections 204 and 206, the section 208 at the base of the horizontal gas pass, and other sections including those along the walls 92 and 94 and the sections above the lower part of the unit including the cyclone furnace and the primary furnace chamber 136. The enclosure for the pressure parts is supported from steel 35 work including such elements as the columns 220 and 222 and the girder 224. The pressure parts such as the drum, headers and tubes are supported on the steel work in manners well known in the art, by means of hangers and drum straps.

40 The normal operation of the described unit involves the flow of steam at pressures such as 350 p.s.i.a. or 600 p.s.i.a. from a nuclear reactor, the flow of steam continuing through the different stages of superheating including the initial superheating in the heat exchanger 16 and the subsequent superheating changes in the gas heated superheater components subject to the heat of the gases originating in the cyclone furnace 130. The steam superheated to a temperature of the order of 1100° F. passes to a stage of a plural stage steam turbine for producing power. However, to provide for a supply of steam from the unit 45 to the turbine for power generating purposes when the nuclear reactor is shut down, the invention involves means whereby steam generated in the lower part of the unit is passed directly to the gas heated superheater components and thence to the turbine. The means for accomplishing this involves one or more conduits such as 250 arranged

to conduct steam from the drum 20 to the superheater inlet header 40. As shown, the conduit 250 leads from the conduit 18 at a position between the drum 20 and the valve 252 which is closed when the nuclear reactor is shut down. Under these circumstances, the valve 254 in the line 34 and the valve 256 in the line 38 are closed and the valve 258 in the line 250 is open. Under these circumstances, the pressure of the steam leaving the drum 20 is reduced to a pressure as that corresponding to the normal pressure of the steam from the nuclear reactor. In addition to providing for the production of power when the nuclear reactor is shut down, the method of operation of the invention provides for advantageous utilization of non-radioactive steam generated by the unit. This steam may act as a washing agent to wash out or dilute radioactive deposits in the superheaters, turbine, condenser and feedwater heater. It also decreases the chance of oxygen pickup in the system, and resulting corrosion and thereby provides for a substantial saving in the original cost of the system in that carbon steel may be used in place of stainless steel for the feedwater heaters and associated equipment.

When the steam from the fuel fired generator passes to the turbine, the furnace wall steam generating tubes are supplied with feed water at an appropriate temperature. This may be attained by a convection economizer interposed relative to the air heater 54 and the convection superheater, the flow of feed water from the economizer being directed to the nuclear steam generator when the superheaters receive only steam from the latter generator.

Whereas the invention has been described with reference to the details of a specific embodiment, it is to be appreciated that the invention is not to be considered as limited to all of the details thereof. It is rather to be considered as of a scope commensurate with the scope of the subjoined claims.

What is claimed is:

1. A method of operating a nuclear steam generating plant including a fuel fired unit normally generating steam at a much higher pressure than the nuclear produced steam and superheating the nuclear produced steam in an initial stage by condensing the high pressure steam and utilizing the heat of the combustion gases to superheat the nuclear produced steam in plurality of later stages to a high temperature, comprising the steps of reducing the pressure of the steam generated at the high pressure, bypassing the reduced pressure steam around the initial stage of the superheating of nuclear generated steam when the generation of nuclear produced steam is ceased, and conducting the steam of reduced pressure directly through the gas heated superheater to wash the gas heated superheater free of any radioactive particles deposited therein during the final superheating stage of the nuclear generated steam.

2. In the operation of a power plant including nuclear means for normally generating relatively low pressure steam, a fuel fired steam generator and superheater for normally generating high pressure steam and condensing that steam in an initial stage of superheating the nuclear generated steam in its passage to a point of use, the fuel fired superheater also involving a gas heated second stage of superheating the nuclear generated steam; the method of operation which includes supplying steam from the high pressure steam generating section of the fuel fired superheater directly to its gas heated superheating section and bypassing an initial and steam condensing stage of initial superheating when the nuclear steam generator is inoperative to effect a washing of the gas heater superheating section free of any radio-active particles deposited therein during the second stage of superheating the nuclear generated steam.

3. In a method of operating a power plant including a low pressure steam generating nuclear reactor, a fuel fired high pressure steam generator for normally superheating the nuclear generated steam by heat transfer from the condensation of high pressure steam and from the gases of the fuel fired component, comprising effect-

ing combustion within a confined zone by burning a fossil fuel at temperatures in excess of 2200° F., transmitting heat predominantly by radiation from the active combustion zone to confined water streams thereby generating steam at a pressure much higher than the pressure of the steam from the nuclear steam generator, transmitting heat by indirect heat exchange from the high pressure steam to the much lower pressure steam from the nuclear reactor, said transmission of heat involving the condensing of the high pressure steam, returning the condensate to the inlets of the water streams subject to the heat of the active combustion zone, further superheating the low-pressure steam from the condensing zone by heat transmission from the combustion gases to confined streams of the lower pressure steam in a heating zone beyond the active combustion zone in a gas flow sense, and when the nuclear reactor is shut down, by passing the condensing zone and superheating the steam from the normally high pressure steam generator by passing it through the gas heated superheating zone.

4. In apparatus of the character described, means for generating relatively low pressure steam, said means being a steam generating nuclear reactor, high pressure steam generating means including a fuel fired furnace having steam generating wall tubes, means for initially superheating the lower pressure steam from the nuclear reactor by condensing the saturated steam from the high pressure steam generating means, a condensate line for returning the condensate from said superheating stage to the water space of the high pressure steam generating means, means including a separately fired gas heated superheater incorporated as a unit with the high pressure steam generating means and subject to the heat of the gases from the fuel firing, a superheated steam supply line leading from the first superheating stage to the separately fired superheater, means for conducting the superheated steam to a point of use, and means bypassing the initial superheating stage and conducting steam from the high pressure steam generator directly through the separately fired superheater to said point of use when the supply of steam from the nuclear reactor steam generator is shut off.

5. The combination of claim 4 wherein said last named means includes the shut-off valves in the high pressure steam line leading to the initial superheating stage and in the condensate return line from the initial superheating stage to the high pressure steam generator, and a valve in the by-pass line leading directly from the high-pressure steam generating section to the gas heated superheater.

6. In an apparatus of the character described, means for generating relatively low pressure steam, another steam generating means including a furnace for effecting the combustion of a fossil fuel to generate a relative high pressure steam, a heat exchange means connected to said lower pressure and high pressure steam generating means wherein the low and high pressure steam generated by said steam generating means, respectively, are brought into indirect heat exchange relationship whereby said low pressure steam is superheated and said high pressure steam condensed, a secondary superheating means exposed to the products of combustion of said fossil fuel, said secondary superheating means being connected with said heat exchanger means to receive the low pressure superheated steam from said heat exchanger means and expose said low pressure superheated steam in heated transfer relationship with the products of said fuel combustion so as to highly superheat said low pressure superheat steam; and a valved bypass means disposed between said high pressure steam generator and said heat exchange means and connecting said high pressure steam generating means to said secondary superheating means whereby steam generated by said combustion of fossil fuel is selectively directed through either said heat exchanger means or said secondary superheating means.

7. In a steam generating and heating arrangement, a first steam generating means adapted to selectively produce relatively high pressure steam and low pressure steam and including a furnace chamber having walls of steam generating tubes, fossil fuel burning means arranged to discharge heating products of combustion into said furnace in heat absorbing relationship with said generating tubes, a steam and water separating drum connected to said generating tubes for receiving either the high pressure or low pressure saturated steam generated in said tubes, said drum having a steam outlet, a second steam generating means producing relatively low pressure saturated steam, said second generating means being adapted to be operatively or inoperatively connected into said arrangement, a heat exchange means in communication with said drum outlet and said second generating means, said heat exchange means adapted to receive in indirect heat transfer relationship the high pressure steam of said first generator means and the relatively low pressure steam of said second generator means whereby said low pressure steam is initially superheated and said high pressure steam condensed, a secondary superheating means exposed to the combustion products of said furnace and heated thereby, a first means connecting said secondary superheater in communication with said heat exchange means whereby said superheated low pressure steam from said heat exchanger is delivered to said secondary superheater means to be highly superheated therein, a second means directly connecting said drum outlet to said secondary superheating means, and valve means operatively disposed in said first and second connecting means for alternately directing steam generated in said first generating means to said heat exchanger when said second generating means is operatively connected in the arrangement and to said secondary superheating means when said second generating means is rendered inoperative.

8. In an apparatus of the character described, a nuclear reactor means for generating relatively low pressure steam, another steam generating means including a fur-

10 nace for effecting the combustion of a fossil fuel to generate a relative high pressure steam, a heat exchange means connected to said low pressure and high pressure steam generating means wherein the low and high pressure steam generated by said steam generating means respectively are brought into indirect heat exchange relationship whereby said low pressure nuclear reactor generated steam is superheated and said fossil generated high pressure steam condensed, a secondary superheating means exposed to the products of combustion of said fossil fuel, said secondary superheating means being connected with said heat exchanger means to receive the superheated steam therefrom and to expose said superheated steam in heated transfer relationship with the products of said fuel combustion so as to be highly superheated thereby, and bypass means directly connecting said second mentioned steam generating means to said secondary superheating means whereby the steam generated by said combustion of fossil fuel is directed thereto, and means for rendering said bypass operative when said nuclear reactor means is rendered inoperative whereby the flow of the fossil generated steam through the secondary superheater effects a cleansing action of said secondary superheating means.
